(57) **CLAIM**

The ornamental design for a traffic control mannequin, as shown and described.

DESCRIPTION

FIG. 1 is a perspective view of a traffic control mannequin; FIG. 2 is front elevational view of a traffic control mannequin;

FIG. 3 is a rear elevational view of a traffic control mannequin;

FIG. 4 is a left side elevational view of a traffic control mannequin;

FIG. 5 is a right side elevational view of a traffic control mannequin;

FIG. 6 is a top plan view of a traffic control mannequin; and, FIG. 7 is a bottom plan view of a traffic control mannequin. The broken lines in FIGS. 1-7 represent environmental structure and forms no part of the claimed design of the traffic control mannequin.

1 Claim, 6 Drawing Sheets
